UNITED STATES PATENT OFFICE.

LEOPOLD F. BURGER, OF RIVERSIDE, ILLINOIS, ASSIGNOR TO INTERNATIONAL HAR-
VESTER COMPANY, A CORPORATION OF NEW JERSEY.

AUTOMATIC FUEL SWITCH.

Application filed March 15, 1920. Serial No. 365,855.

To all whom it may concern:

Be it known that I, LEOPOLD F. BURGER, a citizen of the United States, residing at Riverside, in the county of Cook and State of Illinois, have invented certain new and useful Improvements in Automatic Fuel Switches, of which the following is a full, clear, and exact specification.

My invention relates to internal combustion engines adapted normally to operate on a relatively heavy fuel, such as kerosene, after having been started on a relatively light fuel, such as gasoline or alcohol. In devices of this character it has heretofore been customary to start the engine on the light fuel and then shift to the heavier fuel supply by manually controlled means when in the opinion of the operator the temperature of the engine cylinder is sufficiently high to vaporize the heavier oil. Another means of operation has been to fill an auxiliary receptacle with a predetermined quantity of light fuel on which the engine will start, and when this is exhausted, the engine will receive fuel from the main fuel reservoir containing the heavy fuel. Both of these methods have proved unsatisfactory in practice, since in the first case the operator has no definite means of knowing the temperature conditions within the engine cylinder and may shift to the heavy oil too soon thereby causing a waste of the heavy fuel or he may wait too long before shifting thereby using an unnecessarily large quantity of the expensive light fuel, or in the second case the predetermined quantity of light fuel will be either larger or smaller than necessary, dependent on the initial temperature conditions of the engine, the quantity of mixture and other conditions of operation.

It is an object of my invention to provide means dependent on the temperature conditions within the engine to automatically shift from light to heavy fuel when a certain predetermined temperature is reached or exceeded and to automatically return to the light fuel when the temperature decreases to a certain predetermined point.

Another object of my invention is to provide thermostatically controlled means dependent for its operation on heat absorbed from the gases burned within the engine cylinder to automatically cut off the supply of light fuel to the engine and open the sup-

ply of heavy fuel when a predetermined amount of heat has been absorbed.

A further object is to provide automatic means dependent on the temperature of a thermostatic member for shifting from a light to a heavy fuel when the thermostatic member has attained one temperature on a rising scale and for shifting from the heavy to the light fuel when the thermostatic member has attained a considerably lower temperature on a descending scale.

A still further object is to provide means for quickly or instantaneously changing from fuel of one specific gravity to a fuel of another specific gravity when a predetermined heat condition exists in the engine as contrasted with a gradual changing from one fuel to the other.

The above and other objects will be apparent from the following description of the embodiment of my invention illustrated in the accompanying drawings in which

Figure 1 is a part sectional and part elevational view showing the position of the parts when light fuel is being supplied to the engine;

Figure 2 is a phantom view of the carburetor showing the position of the fuel valves when heavy fuel is being supplied to the engine;

Figure 3 is a plan of the valve tripping mechanism.

The number 5 indicates a carburetor having a chamber 6 adapted to receive a supply of kerosene and a chamber 7 adapted to be supplied with gasoline. The air inlet to the carburetor is indicated at 8 and the outlet for the mixture leading to the intake manifold or engine cylinder is indicated at 9. A passage 10 controlled by a valve 11 and regulated by the needle valve 12 leads from the kerosene chamber to the Venturi passage in the carburetor, the fuel being discharged past the needle valve in atomized condition into the throat of the Venturi passage. Likewise gasoline is supplied from the chamber 7 to the Venturi tube through a passage 13 controlled by a valve 14 and regulated by the needle valve 15. The valves 11 and 14 have elongated stems which are pivotally or otherwise secured to opposite ends of the walking beam or rocker arm 16 which is pivoted to the carburetor between the two valves. A valve tripping arm 18 is also pivoted at one end at 17, the other

end being operatively connected to a push rod 19 for a purpose that presently will be apparent. The walking beam 16 and arm 18 are provided with T heads at one end as shown in Fig. 3 and springs 20, 21 yielding connect corresponding ends of these T-heads to quickly trip the walking beam when shifting from one fuel to the other.

A portion of the exhaust pipe is indicated at 22, the hot gases entering at 23 and passing to the muffler at 24. A thermostatic element 25 composed of an alloy having a relatively large coefficient of expansion is secured at one end within the exhaust pipe, the other end being free to expand against a diaphragm 26 secured between a flange 27 on the exhaust pipe and a flange 28 on the return spring housing 29, slidably mounted within the housing is a piston or plunger 30 urged by the relatively stiff spring 31 against the short arm of a bell-crank lever 32 pivoted at 33 to a fixed part of the engine frame or cylinder. The long arm of the lever 32 is pivoted at 34 to one end of the push rod 19.

Assuming that the engine has been started with the parts in the relative position shown in Fig. 1, gasoline will be fed to the carburetor through the passage 13 and valve 15. Hot exhaust gases from the engine passing through the exhaust pipe 22 will heat the thermostat 25 causing it to expand against the diaphragm 26 and lever 32. As the engine continues to run, the thermostat will continue to absorb heat from the exhaust gases forcing the short arm of the lever 32 to the right against the tension of the spring 31 and raising the long arm of the lever and push rod 19. As the push rod moves slowly upward due to the continued expansion of the thermostat, it carries with it one end of the pivoted arm 18 and the trip spring 20 and 21. This movement continues until the arm 18 reaches dead center position at which time the pull of the springs 20, 21 passes through the pivot point 17 of the lever 18 and walking beam 16. Up to this time there has been no movement of the valves 11 and 14 since the pull of the springs on the beam 16 has been exerted to hold down the end connected to valve 11. However, as the lever 18 is raised beyond dead center, the line of pull of the springs falls above the pivot point 17 and the beam or rocker 16 is instantaneously tripped or rocked to the position shown in Fig. 2, closing the valve 14 and raising the valve 11 to supply kerosene to the carburetor.

The thermostat and its associated parts are so adjusted that when the expansion of the thermostat is sufficient to shift the valves, the engine cylinder will be heated to the proper temperature to operate efficiently on the heavier fuel. Further expansion of the thermostat after the valves have been shift-

ed to supply heavy fuel does not affect the valves but merely raises the lever 18 somewhat higher.

When the engine is shut down, the thermostat 25 cools and contracts away from the diaphragm 26. As this contraction takes place, the spring 31 forces the short arm of the bell crank to the left (Fig. 1) thereby depressing the long arm and lowering the push rod 19 and arm 18. Lowering of the arm 18 does not affect the positions of the valves 11 and 14 until the arm again reaches dead center position on its downward movement, after which further movement will carry the spring 20, 21 below the pivot point 17 and trip the valves from the position shown in Fig. 2 to that shown in Fig. 1. The engine is then ready to be started again on gasoline whenever desired without the operators having to shift any valves or adjust parts.

It will be seen from the above description that my invention automatically shifts from gasoline to kerosene supply when the temperature conditions within the engine are such that the engine will operate efficiently on the heavier fuel, and automatically shifts back to the light fuel when the engine is shut down or for any reason cools below the minimum temperature at which the heavy fuel can be effectively used.

It is also to be noted that there is a considerable range of temperature between the two points at which the valves 11 and 14 are tripped. Thus suppose that the rod 25 has expanded sufficiently to trip the valves to the position shown in Fig. 2 and then immediately begins to cool and contract. The valves 11 and 14 will not be tripped back to the position shown in Fig. 1 until the contraction of the thermostat is sufficient to move the arm 18 in its downward course past dead center, and this may represent a considerable range of temperature. In practice, it is desirable to so adjust the parts that the shift from light to heavy fuel will not be made until the temperature within the cylinder is somewhat above the minimum necessary for the proper use of the heavier fuel, in which case the shift from heavy to light fuel will not take place until the temperature is approximately at or somewhat below this minimum. However, I do not desire to be limited to any definite temperatures for changing from one fuel to another but wish it to be understood that the invention may be modified to effect the changes at any desired temperatures.

While I have described my invention as being adapted to use gasoline and kerosene, these terms are but illustrative of relatively light and heavy fuels, the invention being adapted to the use of any two fuels of different specific gravities such as

different grades of gasoline, alcohol and gasoline, kerosene and crude oil in engines of the Diesel type.

I do not desire to be limited to the specific construction of my invention shown and described, since it will be apparent to those skilled in the art that the invention may be embodied in many modifications without departing from the spirit and scope of the invention defined by the appended claims. An obvious modification would be to omit the piston 30, spring 31, housing 29, and diaphragm 26, substituting therefor a stuffing box through which the thermostat would extend. The extended end of the thermostat would be provided with a slot to receive the short arm of the bell-crank to actuate the fuel switch in both directions. It will also be apparent to those skilled in the art that the thermostat 25 may receive its heat through means other than the exhaust gases. For example, the thermostat may be controlled by the temperature of the cooling water, or it may extend into the combustion chamber of the engine and work equally well.

What I claim as my invention and desire to secure by Letters Patent is:

1. In an automatic fuel switch for internal combustion engines, the combination of separate reservoirs for fuels of different

specific gravities, valve means controlling the passage of the fuels to the engine, an exhaust pipe for the engine, a thermostat secured at one end within the exhaust pipe, 35 the other end being free to move linearly by expansion, and mechanism including a link and bell crank operatively connected to the valve means and adapted to be actuated by expansion of the thermostat for 40 closing the passage for the lighter fuel and opening the passage for the heavier fuel.

2. In an automatic fuel switch for internal combustion engines, the combination of a carburetor having separate reservoirs for 45 fuels of different specific gravities, a fuel passage leading from each reservoir to a common mixing chamber, valves controlling the respective passages, a rocker arm operatively connected at each end to one of the 50 valves, a lever pivoted at one end to the rocker arm between the connections to the valves, resilient means connected to one end of the rocker arm and to the free end of the lever and means dependent upon temperature conditions in the engine for actuating the lever to open one valve and close the other. 55

In testimony whereof I affix my signature.

LEOPOLD F. BURGER.
